UNITED STATES PATENT OFFICE.

CHARLES A. NOVOTNY, OF TOLEDO, IOWA; ANNA NOVOTNY AND E. J. STAYSKELL
ADMINISTRATORS OF SAID CHARLES A. NOVOTNY, DECEASED.

TILE-SETTER.

1,194,220.

Specification of Letters Patent.

Patented Aug. 8, 1916.

Application filed July 20, 1915. Serial No. 40,960.

To all whom it may concern:

Be it known that CHARLES A. NOVOTNY, a citizen of the United States, residing at Toledo, in the county of Tama, State of Iowa, have invented certain new and useful Improvements in Tile-Setters; and I do hereby declare the following to be a full, clear, and exact description of the invention, such as will enable others skilled in the art 10 to which it appertains to make and use the same.

This invention relates to a tile setter.

An object of the invention resides in the provision of a device by means of which tiles 15 may be set in a bored well.

A further object of the invention resides in so constructing the device that the lowermost tile in the well may be manually released and so that the remainder of the tiles 20 will be automatically released when they reach their proper positions.

A further object of the invention resides in the provision of a device which will be simple to manufacture and will be of such 25 construction that it will not easily get out of order.

With these and other objects in view such as will appear as my description progresses my invention comprises the combination 30 and arrangement of parts as set forth in and falling within the scope of the appended claims.

In the drawings: Figure 1 is an elevational view of my device showing the retaining members in the positions they will occupy when a tile is held thereon; Fig. 2 is a similar view showing the near retaining member in the position it will occupy when the device is being withdrawn from a tile; 40 Fig. 3 is a perspective view of my device; and Fig. 4 is a horizontal sectional view, showing the relation of the wings and levers.

Referring to the drawings by reference characters wherein like parts are indicated 45 by like characters throughout the several views: My device consists of a body portion which includes a pair of wings 1 and 2 and a second pair of wings 3 and 4 extending at right angles to the first mentioned 50 pair of wings. Each of these wings is tapered at its upper and lower ends forming a constricted portion 5 at each of the upper and lower ends. This body portion is adapted to be inserted in a hollow tile

and is of slightly less diameter than the 55 inner diameter of the tile.

In order that the tile may be held upon the body portion while it is being lowered into the well, I have pivoted at 6 on the wing 1, a retaining member 7 which extends 60 upwardly and is limited in its outward movement by the contacting of a shoulder 8 thereon with the adjacent face of the wing 4. A similar retaining member 7 is similarly mounted on the opposite face of the 65 wing 2 and its outward movement is limited by the wing 3. The pivot point of this latter member 7 is not shown but it is to be understood that this latter member 7 is constructed and mounted the same as the 70 member 7 which is mounted on the wing 1. Secured to the upper end of each of the retaining members is a link 9 which is pivoted to a lever 10. These levers 10 are pivotally mounted at 11 on the wings 1 and 2. 75 Connected to the levers 10 are operating bars 12 which extend beneath angular braces 13 which act as guides and terminate adjacent the upper end of the body portion. Secured to the upper ends of the bars 12 is 80 a chain member 14 by means of which the retaining members may be operated. A ring 15 is mounted on the upper end of the body portion to which a rope or other suitable member may be attached for lowering 85 the device into the well.

In operating the device it will be inserted into a tile with the retaining members in their innermost positions. The lower end of the device is pushed through the tile and 90 the retaining members moved to their outermost positions so that the upper ends thereof will engage with the lower end of the tile. Of course the device may be inserted into the tile in the opposite direction which will 95 permit the setting of the retaining members in their outermost positions in advance. After the device has been placed in the tile in this manner it may be lowered into the well and when it reaches the bottom of the 100 well, if it is the first tile that is being set, the chain 14 may be pulled upwardly which will draw the upper ends of the retaining members 7 inwardly and permit the device to be withdrawn from the tile. Now when 105 the remainder of the tiles are being set, after they have been lowered into the well, the upper edge of the previously set tile will

engage the outer edges of the retaining members 7 as the device penetrates the previously set tile and the upper ends of the retaining members will be moved inwardly, 5 automatically, so that the tile which is being carried by the device will be released therefrom and will drop upon the next lower tile. When the retaining members are in their outermost positions the shoulders 8 10 will position them so that the links 9 and the levers 10 will extend in angular relation to each other and will consequently permit the inward movement of the retaining members. It will thus be seen that the device 15 will not only be useful in lowering the tiles into the well but it will also position the tiles within the well.

From the foregoing description it will be seen that I have provided a device which 20 will be simple to operate and which is of such construction that it will not readily get out of order.

While I have illustrated and described a particular embodiment of my invention it 25 has merely been for the sake of convenience and I do not wish to be limited to that embodiment as it is obvious that numerous changes may be made in the details of construction without departing from the spirit 30 of the invention or without exceeding the scope of the claims.

What is claimed:—

1. In a tile setter, a body portion 35 consisting of a plurality of wings extending in angular relation to each other and having tapered upper and lower ends, retaining

members pivotally mounted on certain of said wings, links connected to the retaining members at their upper ends, levers pivoted to the body portion and connected to the 40 links and operating bars connected to the levers and extending upwardly in contact with certain of said wings.

2. In a tile setter, the combination with a body portion including a plurality of wings 45 extending at right angles to each other, of retaining members pivotally mounted on certain of said wings, the pivoted end of each of the retaining members having a shoulder thereon arranged to engage the adjacent wing to limit its outward movement and means for moving the retaining members pivotally.

3. In a tile setter, the combination with a body portion including wings extending in 55 angular relation to each other, of retaining members pivoted to certain of said wings, and having shoulders thereon arranged to engage the adjacent wings to limit their outward movement, links connected to said retaining members, levers pivoted to the body portion and to the links and means for actuating the levers, the shoulders being arranged to limit the movement of the retaining members so that the levers and links 60 65 will lie in angular relation to each other.

In testimony whereof, I affix my signature, in the presence of two witnesses.

CHARLES A. NOVOTNY.
